UNITED STATES PATENT OFFICE.

CLAUDE EDWIN MENTZER, OF ALBERT LEA, MINNESOTA, ASSIGNOR OF
ONE-THIRD TO ADAM WIEGAND, OF ALBERT LEA, MINNESOTA.

LOCOMOTIVE DRAW-BAR.

No. 798,745.

Specification of Letters Patent.

Patented Sept. 5, 1905.

Application filed November 12, 1904. Serial No. 232,454.

To all whom it may concern:

Be it known that I, CLAUDE EDWIN MENTZER, a citizen of the United States, residing at Albert Lea, in the county of Freeborn 5 and State of Minnesota, have invented certain new and useful Improvements in Locomotive Draw-Bars, of which the following is a specification, reference being had therein to the accompanying drawings.

This invention relates to an improvement in draw-bars for locomotives; and the object of the invention is the provision of a draw-bar of this type which can be raised to an operative or coupling position or lowered into line with the face of the pilot, so as not to interfere with the effectiveness of the pilot.

A further object of the invention is the provision of fluid-actuated means whereby the coupler may be raised or lowered through the 20 operation of a valve located in the engine-cab.

A still further object of the invention is the provision of fluid-actuating means for withdrawing the coupler-lock, said fluid-actuating means being also controlled through a valve 25 located in the engine-cab.

A still further object of the invention is the provision of means for supporting the coupler, so that none of the weight thereof will be borne by the pilot, and so that the pilot may 30 be removed without removing the coupler or any of the parts thereof.

In the drawings, wherein a preferable embodiment of my invention is shown, and wherein in like numerals of reference refer to similar 35 parts in the several views, Figure 1 is a side elevation of the invention, parts being shown in section. Fig. 2 is a detail view of the mechanism for raising and lowering the coupler and the valve for controlling the same. Fig. 40 3 is a detail view of the mechanism for releasing the coupler-lock and the valve for controlling the same. Fig. 4 is a side elevation of a modified form of the invention, and Fig. 5 is a top plan view of the draw-bar and its 45 supporting mechanism.

Referring now more particularly to the drawings, A designates the pilot-beam of a locomotive, and B a pilot secured in any suitable manner to the front face thereof.

50 C is a clip secured to central portion of the pilot-beam A and provided with a pair of forwardly-projecting ears, between which is pivoted the draw-bar D. The pilot B is pro-

vided with a cut-out portion b, which permits the draw-bar D to swing down in line with 55 the pilot-face when not in use. The draw-bar D carries a coupling-head c, of the usual twin-jaw type.

E E designate a pair of downwardly and forwardly extending plates secured to opposite sides of the clip C or rigidly formed therewith, between which the draw-bar D is adapted to swing. The forward portions of the plates E E are connected by a cross-bar e for a purpose to be hereinafter more particularly 65 set forth.

The draw-bar D is operated by a piston F, working in an air-cylinder F', secured at any suitable point to the under side of the locomotive in rear of the pilot.

G is a piston-rod extending through the front end of the cylinder, to the forward end of which is pivotally attached a link g.

I I designate a pair of levers which are pivotally connected at their upper ends to opposite sides of the draw-bar D and which have their lower ends connected by a bar i.

J J designate a pair of levers pivotally connected at their upper ends to the cross-bar i and at their lower ends to a bearing-plate J', 80 supported upon the heel of the pilot B.

The levers I I are each provided at their lower ends with forwardly-extending hooked portions i', which are adapted when the levers are moved to a certain position to straddle the 85 cross-bar e, secured between the plates E E.

The levers I I and J J are actuated by the link g, which has its forward end pivotally connected to the cross-bar i. When the draw-bar D is in its normal position—i. e., within 90 the cut-out portion b of the pilot B—the levers I I and J J will be knuckled rearwardly; but if the link g is moved forward they will tend to straighten out and will elevate the draw-bar. The forward movement of the link g is continued until the levers pass their central position, when they will begin to knuckle forwardly until the hooked portions i' of the levers I I engage the cross-bar e. The draw-bar D will then be in its coupling position, 100 and the weight of the draw-bar will be borne by the bar e. To move the draw-bar D to its lowermost position, the link g is moved rearwardly. The first movement of the link will cause the levers to straighten out and raise 105 the hooked portions i' off of the bar e, and con-

tinued movement causes the levers to knuckle rearwardly and the draw-bar D to be lowered into the cut-away portion b of the tender B.

The forward and rear ends of the cylinder 5 F are connected by pipes f and f' with a valve-casing K in the engine-cab. The valve-casing K is provided with a cylindrical central bore in which works a rotary valve L and with four equidistant ports K' K² K³ K⁴, communicating 10 with said central bore. The pipes f and f' are connected to the ports K' and K³. The port K⁴ is an exhaust-port, and the port K² communicates by a pipe m with a compressed-air reservoir M. The valve L is provided 15 with two ports l and l', extending through the body thereof. The port l serves to connect the air-pipe M with either the pipe f or f' to cause air to flow to the front or rear part of the cylinder, according as it is desired to raise 20 or lower the draw-bar D, while the port l' serves to connect either of said pipes f and f' with the exhaust-port K⁴, so that when air is being furnished to one end of the cylinder it is being exhausted from the opposite end.

25 The coupler-head c on the draw-bar D is provided with a locking member c'. The locking member c' may be of any suitable construction; but in the form of my invention illustrated in the drawings I have shown 30 it as a reciprocating member sliding on an inclined portion c², formed in the coupler-head c, with antifriction-rollers c³ interposed between said member and the inclined portion. The upper end of the locking member 35 c' projects without the upper face of the coupler-head c and is pivotally connected to the forward end of a link n, the rear end of which is pivotally connected to the cranked portion of an operating-rod N, which is rotatably mounted on the upper face of the pilot-beam B. The operating-rod N extends substantially the entire length of the pilot-beam and is provided at its ends with operating-handles N', by which it may be rocked to 40 withdraw the locking member c'. To provide means for withdrawing the locking member from the cab, an air-cylinder O is secured in any suitable manner to the locomotive-frame in rear of the draw-bar D, in which is adapted 45 to move a piston O'. The piston O' is provided with a piston-rod o, which projects through the front head of the cylinder O and has its forward end pivotally connected by means of a link o' to the cranked portion of 50 the operating-rod N. The piston is normally held against the forward head of the cylinder O by means of a spring o² interposed between the rear face of the piston and the rear head of the cylinder. The forward end of the cylinder 55 is connected by an air-pipe p with a valve-casing P, secured in the engine-cab. The valve-casing P is provided with a cylindrical bore, in which works a rotary valve R, and with three equidistant ports p', p², and 60 p³, communicating with said bore. The port

p' has a pipe connection with the air-reservoir M, the port p² is connected to the pipe p, and the port p³ is an exhaust-port. The valve R is provided with a channel r in the body thereof, which serves to connect either 70 the air-reservoir M with the cylinder O or the cylinder O with the exhaust-port p³. The valve is also provided with a suitable operating-handle. Under normal conditions the valve is turned so that its channel connects 75 the pipe p, running from the front end of the cylinder O, with the exhaust-port p³. The piston O' will then be forced to the forward part of the cylinder and the locking member c' will be held in its locking position. When 80 it is desired to withdraw the locking member c', the valve R is turned until the channel r therein connects the ports p' and p², when air will flow from the air-reservoir M into the forward part of the cylinder, forcing the piston O' back to the rear end of the cylinder against the tension of the spring o² and with it the piston-rod o, which, through its connection with the operating-rod N, withdraws 85 the locking member c'. As soon, however, 90 as the valve R is returned to its initial position the air in the front portion of the cylinder will pass through pipe p, channel r, and exhaust-port p³ and the piston will be returned by its spring o² to its normal position, 95 thereby returning the locking member c' to its locking position.

In Fig. 4 is shown a modified form of the invention, in which the draw-bar and its operating mechanism are supported independently of the pilot, so that none of the weight of said draw-bar will be borne thereby and so that the pilot may at any time be removed from the pilot-beam without removing the draw-bar or any of the actuating mechanism therefor. The construction shown in this form is similar to that shown in the other figures of the drawings, with the exception that the bearing-plate J' instead of being supported upon the heel of the pilot is suspended by 100 braces S S and T T, which have their upper ends secured, respectively, to the front and rear portions of the plates E E.

I do not desire to limit myself to the precise form and construction shown in the drawings, as it is obvious that many minor changes might be made thereto without departing from the spirit of the invention.

Having described my invention, what I claim, and desire to secure by Letters Patent, 120 is—

1. In a locomotive-coupling, a pivoted draw-bar, a coupler-head carried by said draw-bar, a locking member within said coupler-head, fluid-actuated mechanism for raising and lowering the draw-bar, fluid-actuated mechanism for operating the locking member, and means located within the engine-cab for controlling the supply of fluid to said fluid-actuated mechanisms. 125 130

2. In a locomotive-coupling, a pilot-beam, a pilot removably secured to said pilot-beam and provided with a cut-out portion, a draw-bar pivotally secured to the pilot-beam, a stationary bearing-plate supported from the pilot-beam, and mechanism interposed between the bearing-plate and the draw-bar for raising and lowering said draw-bar. 65
- 5 3. In a locomotive-coupling, a pilot-beam, a pilot removably secured to said pilot-beam and provided with a central cut-out portion, a draw-bar pivotally secured to the pilot-beam, and mechanism supported wholly from the pilot-beam for raising said draw-bar to a coupling position or lowering the same within the cut-out portion of the pilot. 70
- 10 4. In a locomotive-coupling, a pivoted draw-bar, a coupler-head carried by said draw-bar, a locking member within said coupler-head, a fluid-actuated mechanism for raising and lowering the draw-bar, and fluid-actuated mechanism for operating the locking member. 75
- 15 5. In a device of the character described, a pivoted draw-bar, a coupler-head carried by said draw-bar, a locking member for said coupler-head, and fluid-actuating means for operating said locking member. 80
- 20 6. In a device of the character described, a pivoted draw-bar, a coupler-head carried by said draw-bar, a locking member for said coupler-head, and means for operating said locking member secured to a stationary portion of the locomotive and a connection between said operating means and the locking member. 85
- 25 7. In a device of the character described, a pivoted draw-bar, a coupler-head carried by said draw-bar, a locking member for said coupler-head, and means for operating said locking member including fluid-actuated mechanism secured to a stationary portion of the locomotive. 90
- 30 8. In a device of the character described, a pivoted draw-bar, a coupler-head carried by said draw-bar, a locking member for said coupler-head, and means for operating said locking member including a cylinder secured to a stationary portion of the locomotive, a piston within said cylinder and a pivoted connection between said piston and said locking member. 95
- 35 9. In a device of the character described, a relatively stationary support, a draw-bar pivotally supported above said support, toggle-links interposed between the draw-bar and the stationary support, and a fixed stop for limiting the forward movement of the toggle-links and supporting the draw-bar in its elevated position. 100
- 40 10. In a device of the character described, a relatively stationary support, a draw-bar pivotally supported above said support, toggle-links interposed between the draw-bar and the stationary support, a stop secured in front of said toggle-links when in their alined position, and a projection carried by one of said links adapted to rest upon said stop and support the draw-bar in its elevated position when the links are forced beyond their alined position. 105
- 45 11. In a device of the character described, a relatively stationary support, a draw-bar pivotally supported above said support, toggle-links interposed between the draw-bar and the stationary support, a cross-bar secured in front of said toggle-links, and a hooked portion secured to one of said links and adapted to engage said cross-bar and hold the draw-bar in its elevated position when the links are forced beyond their alined position. 110
- 50 12. In a locomotive-coupler, a pilot-beam, a pilot secured thereto provided with a central cut-away portion, a clip secured to the pilot-beam and provided with a pair of plates extending downwardly and forwardly into the cut-way portion of the said pilot, a draw-bar pivotally secured to said clip and adapted to swing downwardly between said plates, a cross-bar secured between the lower ends of said plates, a bearing suspended from said plates, toggle-links interposed between the draw-bar and the bearing, one of said toggle-links being provided with a downwardly-extending hooked portion adapted to engage the cross-bar between the plates and support the draw-bar in its elevated position when the toggle-links are moved beyond their alined position, and means for actuating the toggle-links. 115
- 55 13. In a locomotive-coupler, a pivoted draw-bar, a coupler-head carried by said draw-bar, a locking member for said coupler-head, a controller member, and means independent of automatically operable upon the actuation of the controller member for operating said locking member. 120
- 60 14. In a locomotive-coupler, a relatively stationary support, a draw-bar pivotally supported above said support, toggle-links interposed between the draw-bar and the stationary support, a fixed stop for limiting the forward movement of the toggle-links and supporting the draw-bar in its elevated position, and means for actuating the toggle-links. 125
- 65 15. In a locomotive-coupler, a relatively stationary support, a draw-bar pivotally supported above said support, toggle-links interposed between the draw-bar and the stationary support, a fixed stop for limiting the forward movement of the toggle-links and supporting the draw-bar in its elevated position, and automatic means for actuating the toggle-links. 130

In testimony whereof I affix my signature in presence of two witnesses.

CLAUDE EDWIN MENTZER.
